REVERSIBLE OAR

Robert C. Moeller, North Tonawanda, N. Y.

Application February 24, 1948, Serial No. 10,539

4 Claims. (Cl. 9—25)

1

The present invention relates to new and useful improvements in oars for propelling row boats and other small water craft, and more particularly to an oar for propelling a boat forwardly while the rower is facing in a forward direction.

An important object of the invention is to provide a reversible oar in which the propelling action of the oar may be reversed to move the boat either forwardly or rearwardly by a pulling force exerted on the oar handle and without necessitating a reversal of the position of the rower.

A still further object is to provide means for locking the oar in either its forward or reverse propelling position.

A still further object is to provide a device of this character of simple and practical construction, which is efficient and reliable in operation, strong and durable, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view;

Figure 2 is an enlarged vertical sectional view of the rotatable table for the hingedly connected blade and handle portions of the oar;

Figure 3 is a vertical sectional view of the table taken on the line 3—3 of Figure 2, and showing the locking pins holding the sections of the oar for opposite swinging movement;

Figure 4 is a similar view and showing the locking pins holding the sections of the oar in a rigid aligned position for use in a normal manner;

Figure 5 is a horizontal sectional view taken on the line 5—5 of Figure 3; and

Figure 6 is a perspective view of the socket for the oarlock.

Referring now to the drawings in detail wherein, for the purpose of illustration, I have disclosed a preferred embodiment of the invention, the numeral 5 designates a yoke which constitutes an oarlock having a stem 6 extending downwardly therefrom for insertion in an opening 7 in an oarlock socket 8. The socket 8 is of substantially angle iron construction and secured in inverted position on the upper edge of the gunwale 9 of a row boat or other small water craft 10.

The socket 8 is formed in its upper surface with a rectangular shaped recess 11 in which the complementary shaped base 12 of the yoke 5 is con-

2

formably received to hold the yoke or oarlock 5 against horizontal rotation in the socket 8.

A horizontal pin 13 is supported in the upper ends of the yoke 5 and on which is pivoted a tubular lug 14 positioned between the sides of the yoke for vertical swinging movement of an annular base plate 15 positioned above the lug and integrally formed therewith.

The upper surface of the base plate 15 is formed at its central portion with a recess 16 in which is rotatably received a stem 17 extending downwardly from a table designated generally at 18. The recess 16 is enlarged at its lower portion to accommodate the ends of a locking pin 19 inserted transversely of the stem 17 to lock the table in position on the base plate 15 and to provide for the horizontal rotary movement of the table on the base plate.

The table 18 comprises upper and lower annular plates 20 and 21 rigidly supported in spaced relation one above the other by a pair of upstanding posts 22 at diametrically opposite sides of the table. The edge of the lower plate 21 is formed with a downwardly extending flange 23 surrounding the base plate 15 to prevent the entrance of dirt or moisture under the table.

The handle and paddle sections 24 and 25 are pivotally connected to each other by a vertical pin 26 inserted in aligned eyes 27 and 28 of the respective sections.

The handle section 24 is pivoted adjacent its hinged edge on a vertical pin 29 having its ends working in radial slots 30 and 31 of the upper and lower plates 20 and 21, respectively, of the table. The blade section 25 is likewise pivoted adjacent its hinged edge on a vertical pin 32 having its upper and lower ends fixed in the upper and lower plates 20 and 21. Spacing washers 33 are positioned between the upper and lower plates 20 and 21 and the adjacent edges of the handle and paddle sections of the oar.

A pair of locking pins 34 and 35 are slidable vertically in aligned openings 36 and 37 in the upper and lower plates 20 and 21, respectively, for movement of the lower ends of the locking pins into and out of engagement with locking openings 38 in the base plate 15. The upper ends of the locking pins 34 and 35 are connected by a cross bar 39 having a handle or knob 40 at the central portion thereof to raise and lower the locking pins.

Stop collars 41 are formed on the pins engaging the under side of the upper plate 20 to limit the upper unlocking movement of the pin, and upper and lower spring-projected ball catches 42

and 43 are carried by the pins for seating in recesses 44 in the openings 36 to hold the locking pins in either a raised or lowered position.

A locking bar 45 is carried by each of the pins 34 and 35 for movement therewith, the bars extending radially inwardly of the table 18 and formed at their inner ends with an arcuate seat 46 positioned at opposite sides of the aligned hinge eyes or bearings 27 and 28 of the sections of the oar. The locking bars 45 are recessed in grooves 47 in the upper surface of the lower plate 21 when the pins 34 and 35 are moved into their lowermost position, as shown in Figure 3 of the drawings, the hinge bearings 27 and 28 then being free from the locking bar.

In the operation of the device, the oarlock socket 8 is fixed to the gunwale 9 of a boat and the oarlock yoke 5 is removably positioned in the socket with the pivot pin 13 for the base plate 15 extending longitudinally so that the base plate 15 and table 18 mounted thereon may swing vertically in a lateral direction.

The handle portions 24 of the oars are positioned inwardly of the boat immediately in front of a seat 48 thereof so that a person propelling the boat will face forwardly.

The locking pins 34 and 35 are moved downwardly to enter the openings 38 in the base plate 15 to lock the table 18 against rotary movement and the locking bars 45 are lowered into the grooves 47 out of engagement with the hinge bearings 27 and 28.

Accordingly, a rearward pulling force on the handles 24 will also swing the blade portion 25 rearwardly on its pivot 32 to propel the boat forwardly, the pivot pin 29 for the handle portion 24 working in the radial slots 30 and 31 so that the hinge for the sections of the oar will break in the manner as shown by the dotted lines in Figure 5 of the drawings.

When it is desired to rigidly connect the handle and blade sections of the oar for use in a conventional manner, the locking pins 34 and 35 are raised to free the lower ends of the pins from the openings 38 in the base plate 15 and to move the locking bars 45 upwardly at opposite sides of the hinge bearings 27 and 28, whereby to lock the sections of the oars against pivotal or breaking movement at their hingedly connected ends and the sections of the oar are then locked to the table 18 which is free to rotate on the base plate 15 during forward and backward movement of the oar.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended

by the spirit of the invention as herein described and within the scope of the appended claims.

Having described the invention, what is claimed as new is:

- 5 1. An oar comprising an oarlock including a stationary base plate, a table rotatably mounted on the base plate, handle and blade oar portions pivotally connected to each other and individually pivoted to the table for opposite swinging movement of said portions, and means locking the table to the base plate and also locking the portions of the oar to each other and arranged for opposite locking and unlocking movement.
- 10 2. An oar comprising an oarlock including a stationary base plate, a table rotatably mounted on the base plate, handle and blade oar portions pivotally connected to each other and individually pivoted to the table for opposite swinging movement of said portions, said table and base plate having lockable engagement, and means simultaneously locking the portions of the oar to the table and unlocking the table from the base plate.
- 15 3. A combined oar and oarlock and comprising a fixed yoke, a base plate pivoted to the yoke for vertical swinging movement, a table rotatably mounted on the base plate, handle and blade oar portions pivotally connected to each other and individually pivoted to the table for opposite swinging movement of said portions, slideable locking pins locking the table to the base plate, and locking bars carried by the locking pins for locking the portions of the oar rigidly to each other, said locking pins and locking bars being oppositely movable into and out of locking position.
- 20 35 4. An oar comprising an oarlock including a stationary base plate, a table rotatably mounted on the base plate, handle and blade oar portions pivotally connected to each other and individually pivoted to the table for opposite swinging movement of said portions, and means locking the table to the base plate and also locking the portions of the oar to each other and arranged for opposite locking and unlocking movement, said means comprising a pair of slideable locking pins for the table and base plate and locking bars carried by the locking pins for locking the portions of the oar to each other.

ROBERT C. MOELLER.
